UNITED STATES PATENT OFFICE

DORSEY M. WIRTH, OF BUCYRUS, OHIO

BELT BUCKLE

Application filed December 30, 1930. Serial No. 505,644.

This invention is a continuation in part of application Serial No. 466,245 now in course of prosecution in the Patent Office and relates to expanding belt buckles wherein the expanding member is a spring, incorporated in a new and novel manner whereby a superior belt buckle admitting of a great variety of included modifications of useful and practical nature may be constructed.

10 The objects of this invention, its nature, and its composition and arrangement and combination of parts will be readily understood by any one acquainted with the art to which this invention relates upon consulting the following descriptions of the drawings, in which:—

Figure 1 is a front view of one form of buckle contemplated by this invention.

Figure 2 is a front view of another form of belt buckle included in this invention.

Figure 3 is a third form of belt buckle contemplated by this invention viewed from the back of the belt.

Figure 4 is a detailed perspective view of certain parts of the buckle.

Figure 5 is a longitudinal sectional view taken approximately on the line 5—5 of Figure 1.

Figure 6 is a longitudinal sectional view taken approximately on the line 6—6 of Figure 2.

Figure 7 is a longitudinal sectional view taken approximately on the line 7—7 of Figure 3.

Figure 8 is a perspective view of one of the parts used in the form of the buckle disclosed in Figure 3.

Figure 9 is a detailed enlarged view of another suggested form of the spring expanding member which might be incorporated in any of the forms of buckles alluded to in this application.

Referring to the drawings in detail, the numeral 5 designates generally the belt which has the end 6 secured to the buckle and the end 7 or the free end of the belt adapted to be inserted in the buckle and to be held by the belt retaining means of the buckle, which engages in the holes 10 of the belt portion 7.

50 Referring to Figures 1, 2 and 3 it will be

observed that an element generally designated 11 is common to these forms. This belt connector element 11 is shown in detail in Figure 4, and as illustrated, comprises a closed loop formed by bending a bar or wire 55 into a U, extending the sides 12 of the U laterally away from each other as at 13 and bending them again, and this time inwardly as at 14, from which point they proceed right angularly and directly into end abutting relation meeting at the point 15. A roller sleeve 15 is for convenience and to increase the smoothness of the association of the belt end with the element 11, is placed so that it covers the joint already indicated at 15. Common 60 also to the forms of the buckles disclosed in Figures 1, 2 and 3 is a U-shaped yoke member 17, composed of bar material, and formed right angular for the greater portion of its extent. In the form of buckle shown in Figure 1 the ends of the yoke member 17 opposite its bight portion 18 are spread outwardly and then directed upwardly to meet and to be attached to a generally oval-shaped buckle body 19. In the form of the 65 buckle illustrated in Figure 2 the ends of the sides of the member 17 opposite the bight portion 18 diverge like the end portions of the form of the buckle illustrated in Figure 1 but they merge at their outward 70 extremities with a buckle body 20 which is likewise with the buckle body 19 disposed generally in a plane displaced from, but parallel with the plane of the member 17.

The buckle body 20 resembles very much one 75 side of an ordinary belt buckle. In the form of Figure 2 the forward ends of the yoke member 17 are joined by a bar 21 on which is centrally and pivotally mounted a tongue for entering the belt holes 10 and cooperating 80 with the buckle body 20 in adjustably securing the belt end 7 in the buckle. The buckle body 19 of the form illustrated in Figure 1 has a hook 23 illustrated in dotted lines in Figure 1 and in full line in Figure 5 which, as 85 shown in Figure 5, is adapted to engage in the belt holes 10.

In the form of buckle shown in Figure 3 the forward ends of the member 17 are joined in spaced relation with each other by a heavy 90

100

block or bar 24 which has pivots, one on each end as indicated at 25. The pivots 25 are journaled in ears formed on a buckle body generally designated at 27. This form of buckle body is substantially square, and is composed of a substantially flat rectangular body portion 28 which has curved flange on opposite sides brought inwardly as illustrated. The belt end 7, of course, is adapted 10 to be confined by the flanges 29. The ears are disposed on the ends of the flanges 29 and are disposed at right angles to the body portion 28, but spaced therefrom.

Common to each form of buckle is the disposition of the legs or sides of the connector member 11 so that they slide through holes formed in the bight portions 18 of the yoke member 17. These holes are clearly seen in Fig. 8 at 30. Mounted on each of the members 11 is a coiled spring 31, of the expanding type. The spring is disposed on each leg 12 of the member 11 and continues around the curved portion 12a. The ends of the spring are adapted to abut the inner face of the bight portion 18 of the member 17. It will at once be recognized that with a properly made spring, there will be resilient resistance to drawing the member 11 and the member 17 in opposite directions, and this fact 25 supplies the resilient expanding character of the invention, whereby added comfort and efficiency is brought to belt buckles.

Reference to Figure 9 will disclose a modification of the connector member 11 which 30 is designated generally 11a. In this form, a single bar 32 is slidably mounted in a hole in the bight portion 18 of the yoke member 17, and a wide flat loop 33 is formed by bending the bar 32 laterally at right angles, and 35 then bending it so as to form a straight portion directed oppositely and parallel to the first lateral bend. The second mentioned portion extends as far in the opposite direction, and then is bent again to provide a 40 portion which returns in a manner parallel to said second mentioned portion until it almost abuts the bar 32. A coiled spring 34 is disposed to have one end abut the bight portion 18, and the other end abuts a disk 45 or washer 35, whereby a resilient spring action similar to that obtained in the forms illustrated in Figures 1, 2 and 3 is obtained.

It is to be definitely understood that I do not desire to limit the application of this 50 invention to the particular modifications set out herein to illustrate the principles thereof, and any change or changes may be made in material and structure and arrangement of parts consistent with the spirit and scope 55 of the invention.

What is claimed is:—

1. A belt buckle of the type described comprising a belt connector loop, a U-shaped yoke carrying the loop slidably in its bight, 60 a spring on the loop for resisting longitudinal separation of the loop and the yoke, a buckle body connected with the yoke, a belt hole engaging tongue on the buckle body for adjustably retaining one end of a belt, the other end of the belt being fixedly retained 70 by attachment to the loop.

2. A belt buckle of the type described comprising a closed belt connector loop to which is fixedly attached one end of the belt, a U-shaped yoke having an apertured bight 75 portion for slidably receiving, in longitudinal relation, the side members of the loop, a coiled spring received on the legs and bight portion of the connector loop for abutting the bight of the yoke, a buckle body attached on the free ends of the yoke, a belt hole engaging tongue fixedly mounted on the underside of the buckle body.

3. A belt buckle of the type described comprising a closed belt connector loop, a U-shaped yoke having its bight portion apertured to slidably receive the side members of the loop, a coiled spring on the side members of the loop adapted to abut the bight portion of the yoke, a buckle body attached on the free ends of the legs of the yoke, a cross bar between the legs of the yoke adjacent the buckle body, a swingable tongue carried on said cross bar.

4. A belt buckle of the type described comprising a closed belt connector loop to which is fixedly attached one end of the belt, a U-shaped yoke having an apertured bight portion for slidably receiving, in longitudinal relation, the side members of the loop, a coiled spring received on the legs and bight portion of the connector loop for abutting the bight of the yoke, a buckle body attached on the free ends of the yoke, a belt hole engaging tongue fixedly mounted on the underside of the buckle body, said yoke having a cross member joining the free ends of its legs, a pivot on each end of the member, said buckle body having apertured ears extended on the underside thereof for journaling said pivots.

In testimony whereof I affix my signature.
DORSEY M. WIRTH.
